UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,316,814.

Specification of Letters Patent. Patented Sept. 23, 1919.

Application filed November 26, 1917. Serial No. 203,878.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to the class of type-10 writing machines illustrated in the patent to Wernery and Smith, No. 1,132,055, in which a web which is fan-folded longitudinally is led through a typewriting machine, so that the outer ply thereof may receive the ink-ribbon impressions, while the 15 inner plies receive carbon duplicates of said impressions.

After being written, the web is severed into typed pages. The carbon copies are 20 usually intended merely for office use, and, therefore, may be upon inexpensive paper; but since the outermost ply, which is the ribbon copy, is usually intended to be sent out to a customer or correspondent, such 25 cheap paper as would be found satisfactory for office use, is not of sufficiently good quality for sending to the customer or correspondent; and since all the copies are originally parts of an integral web, a difficulty is presented.

If it be found imperative for the outer or original copy to consist of expensive paper, then, of course, all the remaining copies must be upon the same paper, thus increasing 35 the expense to a prohibitive point, especially where there are many plies of the fan-fold web. For this reason, the use of machines of the class shown in said patent is limited. Moreover, the expensive class of 40 paper is usually heavy, and it is not practicable to make as many clear carbon copies upon heavy paper as are usually required. Again, the sheet which is sent out to the customer may require a rather large heading, 45 which heading is not required upon the office copies, and hence the objection arises that the inner or carbon copies (which must be of the same length as the outer copy) are unnecessarily long and wasteful.

50 One of the objects of the present invention

is to enable the user to preserve the advantage of using a fan-fold web in making manifold copies thereon, all in perfect register, and to have these carbon copies made upon cheap paper, while enabling him also to have the original or ink-ribbon copy made upon a better grade of paper, while preserving the desired register, and further to permit the adoption of an outer or original sheet or page which is longer than any of the carbon copy sheets or pages.

Other features and advantages will hereinafter appear.

In the accompanying drawings, 65 Figure 1 is a perspective view of the fan-fold typewriting machine disclosed in said Wernery and Smith patent, but modified to carry out the present improvements in one form; the parts shown in normal positions. 70

Fig. 2 is a detail of a clip for temporarily holding a web or sheet in register.

Fig. 3 is a side elevation of the machine, largely in section.

Fig. 4 is a rear view, showing a detail of 75 a means for feeding to the machine a separate web.

To carry out the invention, there is employed, in addition to the inexpensive fan-fold web 10, a separate web 11 of such high 80 quality of paper as may be desired, and this is fed off from a roll 12 or other supply and led through the typewriting machine 13 in such relationship to the fan-fold web that the ink-ribbon copy will be made upon 85 the single ply or main web 11, while all the carbon copies are made upon the plies of the fan-fold web 10. The sub-carriage 14, which is employed in the said Wernery and Smith patent for shifting the carbons 15 back from 90 time to time between the plies of the fan-fold web, is provided with an extra carbon 16, which lies between the fan-fold web 10 and the main or outer web 11, so that this carbon 16, which writes upon the outer ply 95 of the fan-fold web, will be shifted along with the others.

The platen 18 of the machine herein illustrated, like that shown in the Wernery and Smith patent, is journaled by its axle 10

in a swing frame comprising ends 7, which are journaled on a shaft 8. The platen axle is geared to the line-space wheel 45 by a pinion 9^a, fast on the axle 6, and meshing with a pinion 9^a, fast on the shaft 8, said latter pinion also meshing with a pinion 9, which is fast to the shaft 6^a of the line-space wheel 45. The platen 18 is held against the feed rolls 23 by means of a handle 9^c on the swing frame caught by the usual pivoted hook 9^d. The typist may swing the swing frame up by pushing the hook 9^d rearwardly to release the handle, and then drawing on the handle, with the result that the platen 15 swings up until webs 10, drawn along the sub-carriage 14, can be stretched straight forwardly under the platen.

The fan-fold web 10 may be introduced in the machine at its rear side and carried forwardly and down and up around the platen 18 in the usual way, and its leading edge may be passed up under the usual front feed rolls 17, and led under the usual web-severing knife 39, and the edge of the web may 25 be brought into coincidence with the cutting edge of the knife. While the web is lightly held by the rolls 17, (the usual bottom feed rolls 22, 23 being cast off by the usual key 24 preparatory to the insertion of the webs), 30 the single ply web 11 may be introduced at the rear and led along below the fan-fold web and over a table 18^a which is arranged upon the supplemental carriage 19, which, in said patent, supports the fan-fold web 10 35 as it runs into the typewriting machine; said carriage being in the nature of a rearward extension from the usual platen carriage 20 of the Underwood typewriting machine. The single ply web 11 is led along 40 forwardly beneath the carbon 16 which underlies the fan-fold web, and passes over a bar 21, and thence downwardly around under the platen 18 and assembled under or around the fan-fold web 10, and thus it may be 45 led upwardly (the feed rolls 22, 23 remaining cast off from the platen) and over the fan-fold web 10 until the leading edge of the single ply web is brought to a gage 25, beyond the knife edge 39, and resting upon 50 the overlying table 25^a.

The bar 21 may be in the form of a rolled rim provided upon the upper portion of a paper shelf 26, which extends forwardly and downwardly to curve around the under 55 side of the platen; and this bar 21 may be placed some distance below the bar 24^a, over which the fan-fold web 10 turns in descending to the platen. The extra carbon 16 may, if desired, pass over the bar 24^a, 60 although preferably it passes between 24^a and the web 11, and may rest upon a table or shelf 26^a, extending back from the usual tie-rod 26^b which connects the side plates of supplementary carriage 19, said shelf lying

sufficiently low to clear the carbon carriage 14, as illustrated at Fig. 3. The rear end of this carbon 16 is caught upon a special blade 27 provided upon an extension 28 at the lower front portion of the carbon carriage 14. The special web-supporting table 18^a may 70 be supported at its forward end upon hangers 29 depending from the side bars of the carriage 19, and at its rear end upon a cross-bar 30 connected by brackets 32 to hangers 31 dropped from the side bars of 19; said 75 hangers 31 being at the sides of the machine, and having rolls 33 to run upon a rail 34.

During the aforesaid manipulation of the main or outer web 11, the leading end of the fan-fold web 10 may be held in its previously 80 gaged position, by means of said front rolls 17. These web units may thus be brought into perfect relative register as to the forms printed thereon, even though their leading edges may be one in advance of the other. 85 It will be understood that the forms on the outer web 11 may have extensive headings printed thereon, and hence may be longer than the forms on the fan-fold web 10, which need no headings. The outer web is originally advanced a corresponding distance beyond the fan-fold web, so as to bring their forms into relative register; and it will be understood that when the webs are subsequently divided into pages, the page 90 95 severed from the outer web will be longer than those which are severed from the fan-fold web.

When the outer web 11 has been brought up against its gage 25, the collated webs 100 may be pressed by the restored feed rolls 22, 23 against the bottom of the platen. The rolls 17 may remain effective.

The gage 25 may, if desired, be omitted, and the main or overlying web 11 may have 105 a line or mark printed thereon to coincide with said top edge of the fan-fold page, so that the operator may need only to draw the outer sheet 11 up until he sees that such printed line registers with the tearing edge 110 of the knife. In other words, the webs may, if desired, be originally collated to the knife edge, the fan-fold leading edge being first brought to said edge, and there held lightly by the pressure of rolls 17, while the outer web 11 is advanced thereover to bring the line or mark thereon into register with said knife edge. 115

Then the typing of the page may proceed. If such page is to be completely filled out by 120 the typing, the line-feeding operations will finally bring the leading edge of the web 10 into engagement with a gage 35. But if the typing is not to fill up the page, the operator will finally need to advance the web 10 125 to said gage 35, preferably after the carbon sheets have been shifted back for the succeeding form or page.

Whether the page has been fully or only partly filled up by the typing, the operator proceeds to release the front rolls 17 (each of which for this purpose is mounted upon an arm 17^a of usual construction, pivotally connected to a grooved short shaft 17^b of the usual type, and held down by the usual spring 17^c), and then swing up the platen 18 to straighten out the webs (see Fig. 6 in said patent), and then, by manipulating the usual handle 38, push backwardly the carriage 14 which carries the carbons, so that while all the sheets are substantially straight or flat, said carbons 15, 16 will be returned to positions required for writing the succeeding page upon the webs. The operator may then swing the platen down to normal position, and release the rolls 22, 23 by depressing the key 24, and then advance the outer web 11 to a gage 40, to bring it to position for severance by the knife 39. The gage 40 may be adjusted to allow for a greater bottom margin on the page torn from 11 than on the page torn from 10. In fact, the position of gage 40 may allow for both top and bottom additional margins on 11. The front rolls 17 are restored and remain on the paper during the manipulation of the outer web 11, but do not interfere with the adjustment of 11, since they press but lightly, although with sufficient force to hold the inner web 10 against accidental displacement during the described manipulation of web 11. The operator may now 35 tear off simultaneously both the typed page of the outer web 11, and also the corresponding portion of the fan-fold web 10, by the use of said knife 39 which extends along the front of the platen.

40 The webs 11 and 10 having been severed and the severed pages removed, the operator may (the feed rolls 22, 23 remaining cast off) advance the outer web 11, if necessary, to its gage 25, and then the feed rolls 22, 23 45 may be restored and the typewriting of the next page may proceed.

It will be understood that if the pages from the outer web 11 are to be of the same length as those from the inner web 10, the 50 gages 25 and 40 need not be used, but that both webs may be set up to the single gage 35 preparatory to tearing off the pages from the webs by means of the knife 39.

The advance of the outer web 11 into the 55 machine may be aided by power derived through the web 10, the latter being drawn forward by means of the usual connection to the line-feeding mechanism of the typewriter, a part of which is seen at 45, Fig. 1.

60 The incoming web 10 is pressed by a roll 46 against a companion roll 47; said roll 46 being for this purpose mounted upon arms or bail 48, pressed forwardly by spring 49, to press the web against the 47. The latter is confined between the bars of the 65 supplemental carriage 19 of the typewriter, and so travels to and fro with said carriage in letter-feeding direction. Said roll 47 is connected by a spline 50 to its axle 51, the latter mounted in stationary supports 52 70 upon the main frame of the typewriting machine and having at its end a pulley 53 connected by a belt 54 to a pulley 55 upon a shaft 56, by which the supply spool 12 of the single-ply web 11 is rotated, and the web is 75 caused to fall therefrom in a loop 57, which loop is sufficiently flexible to accommodate the travel of the table 18^a and the typewriter carriage 19, while the spool 12 remains stationary. Additional pulleys 58 80 and 59 may be provided for varying the speed of rotation of the spool 12, when desired. Preferably, the driven pulley shaft 56 carries a roll 61 which has a contact with the periphery of the spool 12, to drive the 85 same to pay off the web 11 at the same speed as that at which the web 10 advances; and the belt 54 may consist of helically-wound wire coils, to make it extensible. A spring 61^a may keep the driving roll 61 in contact 90 with the outer coil of the spool 12, as the latter unwinds; said spring connected to an arm or arms 61^b which carry said roll.

It will be seen that the fan-fold web and the outer web constitute separate webs, and 95 the inner one may be held by the pressure of the rolls 17, while the outer web is advanced thereover. It will further be apparent that certain features of the invention are applicable for separate webs whether said webs 100 are single ply, or fan-fold, or otherwise folded. For example, the machine may be employed for typewriting upon numerous single ply webs, each led from a roll or other source of supply, and that one or more of 105 said webs may be advanced to one of said gages 25, 35, 40, (the rolls 22, 23 being released) while one or more of the remaining webs may be further adjusted to the other of said gages, in the manner already indicated. To avoid misalignment of the forms among the various webs, due to creeping, the single webs may be separately re-gaged preparatory to typing each page or form 110 thereon. The webs may be set one at a time 115 to the adjustable lower gage 35. That is to say, the innermost web may be brought first to the gage 35, and there held by the pressure of the rolls 17; or said rolls may be cast off and the web may be held by clips 62, one 120 clip upon each side of the main collating table 63. Then the second web is adjusted to the same gage, and gripped by the other or alternate clips 64 at the sides; whereupon the first or advanced clips 62 are released 125 by the operator; since the clips 64 will hold both plies. Then a third web may be advanced to the same gage 35, and held by the

first clips 62, after which the clips 64 are released; and so on, a single pair of clips, one at each side of the machine, always sufficing to hold all of the previously registered webs. 5 Then, if desired, one or more additional or outer webs (having long pages thereon) may be adjusted to the top adjustable gage 40, while the inner webs remain clipped; and the same clips will answer for retaining 10 one or more of the outer webs, if necessary, during the progress of the collating operation. It will be seen that by using the gages and clips in this manner, the difficulty heretofore experienced with the use of separate 15 plies of webs which are printed with forms may be avoided, the difficulty consisting in the creeping of the webs, due to the rolling of the assembled webs around the revoluble platen; the outer web always tending to 20 travel more rapidly than the inner web, so that in time the outer web will creep so far that the registration of the form lines on the various webs will be lost. By the present means, there may be secured re-registration 25 of the lines or forms upon the various single-ply webs preparatory to the writing of each page, so that the difficulty due to creeping is avoided. The gage 25 may have a range of adjustment greater than the length 30 of a printed form, so as to be usable for a top sheet whether the lower sheets are gaged by 39 or 35. After the webs are all set up to one or both of the gages 35, 25, the feed rolls 22, 23 may be restored (also the rolls 35 39 if desired), and the platen knob 65 may be turned to roll all the webs backwardly until the edges of the lower webs recede 40 from the gage 25 to the upper edge of the knife 39; whereupon the typing may proceed. But if the top web has been set up to the gage 40, there may be provided a line or mark upon said top web, to coincide with the top edges of the bottom webs, so that the operator needs only to retract the webs far 45 enough to bring said line or mark into register with the knife. It will be seen, moreover, that at any time, after typing a page, the lower single webs one at a time may be adjusted to the knife and torn off accurately, 50 so that thereafter they will all be sure to be in proper register when their leading edges are adjusted to their gage 35.

The details of the preferred forms of collating tables and gages will be understood 55 from the drawings; the table 63 carrying the overlying collating table 25^a fixed thereon, 25^a having downwardly-turned side flanges to connect it to 63. Gage 35 is retained in any position by means of a thumb-screw 65, extending down through a narrow 60 slot 66 in the table 63. Gage 25 is retained wherever adjusted by means of a thumb-screw 67 extending down through the same slot 66; said gage 25 consisting of a flange 65 bent down from a top collating table 68.

Upon the under side of 68 is a boss 69 for the thumb-screw 67; said boss passing down through a slot in 25^a, and also fitting in a slot in a plate 70 extending up from the gage 35. The slots, boss and screw may coöperate 70 with the slots to guide the gages up or down; and gage 25 may be partly guided by ears 71 pendent from the opposite sides thereof to fit over the side edges of the table 25^a. The top gage 40 may be secured where adjusted, 75 by means of a set-screw 72, threaded into a boss 73 formed upon a bridge 74 which is erected upon the table 63 and crosses above the plate 75 from which said gage 40 rises. Table 63 may also carry the clips 62, 64, and 80 the mounts 76 for the arms 17^a carrying the rolls 17.

Certain features of the invention are applicable to flat platen typewriters.

Variations may be resorted to within the 85 scope of the invention, and portions of the improvements may be used without others.

Having thus described my invention, I claim:

1. In a typewriting machine, the combination with a revoluble platen and means for supporting and guiding a fan-fold web to and around said platen, of additional means for supporting and guiding a separate web to pass around the platen in front of said 90 fan-fold web, means for carrying carbon or manifolding sheets between the plies of the fan-fold web and also between the fan-fold web and the separate web, said carbon-carrying means shiftable to retract the carbons, 95 and means to afford a bodily shift of the platen to afford clearance, to permit substantial straightening of said webs.

2. In a typewriting machine, the combination with a revoluble platen, of a carbon-carrier mounted for movement toward and away from said platen for alternately traveling with a fan-fold web and shifting the carbons back along the web, means by which the fan-fold web is guided down to the 100 platen to pass around the under side and up in front thereof, and a table or support extending beneath said carbon-carrier for supporting a separate web to be led around the under side of the platen and up in front 105 thereof to overlie the fan-fold web, said carrier including means for carrying a carbon to lie between said fan-fold web and said separate web, and said platen shiftable to afford clearance to permit both webs to be 110 straightened sufficiently to admit of retraction of the carbons therealong.

3. In a typewriting machine, the combination with a revoluble platen, of a carbon-carrier mounted for movement toward and away from said platen for alternately traveling with a fan-fold web and shifting the carbons back along the web, a bar by which the fan-fold web is guided down to the 115 platen to pass around the under side and up 120 in front thereof to overlie the fan-fold web, said carrier including means for carrying a carbon to lie between said fan-fold web and said separate web, and said platen shiftable to afford clearance to permit both webs to be straightened sufficiently to admit of retraction of the carbons therealong.

130

in front thereof, and a table or support extending beneath said carbon-carrier for supporting a separate web, a second bar or device over which the separate web is guided downwardly to be led around the under side of the platen and up in front thereof to overlie the fan-fold web, said second bar arranged beneath the first bar, said carrier including means for carrying a carbon to lie between said fan-fold web and said separate web, and said platen shiftable to afford clearance to permit both webs to be straightened sufficiently to admit of retraction of the carbons therealong, and a separate support for said extra carbon, said support extending rearwardly beneath said carrier in position to clear the same. 70 75

15. 4. In a typewriting machine, the combination with a revoluble platen and a carriage mechanism, of a carbon-carrier mounted upon said carriage mechanism for movement toward and away from said platen, 20 said carriage mechanism including means over which the fan-fold web is guided from the carbon-carrier down to the platen, to pass around the under side and up in front thereof, and a table or support upon said carriage mechanism beneath said carbon-carrier for supporting a separate web to be led around the under side of the platen and up in front thereof to overlie the fan-fold web, said platen shiftable to afford clearance 25 to permit both webs to be straightened sufficiently to admit of retraction of the carbons therealong, and said carbon-carrier including means for carrying an additional carbon to lie between said fan-fold web and 30 said separate web.

5. In a typewriting machine, the combination with a revoluble platen, of a carbon-carrier mounted for movement toward and away from said platen for alternately traveling with a fan-fold web and shifting the carbons back along the web, means on which the fan-fold web is guided down to the platen to pass around the under side and up in front thereof, a table or support beneath 40 said carbon-carrier for supporting a separate web to be led around the under side of the platen and up in front thereof to overlie the fan-fold web, said carrier including means for carrying a carbon to lie between 45 said fan-fold web and said separate web, and said platen shiftable to afford clearance to permit both webs to be straightened sufficiently to admit of retraction of the carbons therealong, and a separate support also beneath said carbon-carrier for said extra carbon. 50

6. In a typewriting machine, the combination with a revoluble platen, of a carbon-carrier mounted for movement toward and away from said platen for alternately traveling with a fan-fold web and shifting the carbons back along the web, means on which the fan-fold web is guided down to the platen to pass around the under side and up 60 in front thereof, a table or support beneath 65

said carbon-carrier for supporting a separate web to be led around the under side of the platen and up in front thereof to overlie the fan-fold web, said carrier including means for carrying a carbon to lie between 70 said fan-fold web and said separate web, and said platen shiftable to afford clearance to permit both webs to be straightened sufficiently to admit of retraction of the carbons therealong, and a separate support for 75 said extra carbon, said support extending rearwardly beneath said carrier in position to clear the same. 80

7. In a typewriting machine, the combination with a revoluble platen and a carriage mechanism, of a carbon-carrier mounted upon said carriage mechanism for movement toward and away from said platen, said carriage mechanism including means over which the fan-fold web is guided from 85 the carbon-carrier down to the platen to pass around the under side and up in front thereof, a table or support upon said carriage mechanism beneath said carbon-carrier for supporting a separate web to be led 90 around the under side of the platen and up in front thereof to overlie the fan-fold web, said platen shiftable to afford clearance to permit both webs to be straightened sufficiently to admit of retraction of the carbons therealong, and said carriage including 95 means for carrying an additional carbon to lie between said fan-fold web and said separate web, and a separate table or support mounted upon said carriage mechanism beneath said carbon-carrier to support said extra carbon. 100

8. In a typewriting machine, the combination with a revoluble platen, of means at the introductory side of the machine for supporting a web, separate means at the introductory side of the machine for supporting a separate web, means for guiding and assembling said webs in superposed relation and carrying them around said platen, and means for retracting a carbon extending between said webs, said platen being shiftable for clearance to permit straightening of said webs sufficiently to allow the carbon to be retracted. 105 110 115

9. In a typewriting machine, the combination with a revoluble platen, of means at the introductory side of the machine for supporting a web, separate means at the introductory side of the machine for supporting a separate web, means for guiding and assembling said webs in superposed relation and carrying them around said platen, means for retracting a carbon extending between said webs, said platen being shiftable for clearance to permit straightening of said webs sufficiently to allow the carbon to be retracted, gaging means for said webs at the delivery side of the platen, and means at the delivery side 120 125 130

of the platen for retaining one of said webs while another web is advanced thereover at the operation of gaging the same.

10. In a typewriting machine, the combination with a revoluble platen, of means at the introductory side of the machine for supporting separate superposed webs, and guiding said webs to and around said platen, means for retracting a carbon extending between said webs, said platen being shiftable for clearance to permit straightening of said webs sufficiently to permit the carbon to be retracted, gaging means for said webs at the delivery side of the platen, and means at the delivery side of the platen for retaining one of said webs while another web is advanced thereover at the operation of gaging the same.

11. In a typewriting machine, the combination with a revoluble platen, of means for guiding superposed separate webs to and around said platen, means for retracting a carbon extending between said webs, said platen being shiftable for clearance to permit the webs to straighten out sufficiently to allow retraction of the carbon, gaging means for the leading edges of said webs, and means at the delivery side of the platen for holding one of said webs in its gaged position while another web is advanced thereover for gaging.

12. In a typewriting machine, the combination with a revoluble platen, of means for guiding superposed separate webs to and around said platen, means for retracting a carbon extending between said webs, said platen being shiftable for clearance to permit the webs to straighten out sufficiently to allow retraction of the carbon, gaging means for the leading edges of said webs, and means at the delivery side of the platen for holding one of said webs in its gaged position while another web is advanced thereover for gaging, said holding means in the form of a roll to run lightly upon the outer web, the roll rotating to permit the advance of the outer web while maintaining pressure upon the inner web to hold it from stirring.

13. In a typewriting machine, the combination with a revoluble platen, of means for guiding superposed separate webs to and around said platen, means for retracting a carbon extending between said webs, said platen being shiftable for clearance to permit the webs to straighten out sufficiently to allow retraction of the carbon, gaging means for the leading edges of said webs, and a roll at the delivery side of the platen for holding one of said webs in its gaged position while another web is advanced thereover for gaging; said roll constructed to run lightly upon the outer web, and rotating to permit the advance of the outer web while maintaining pressure upon the inner web to

hold it from stirring, said roll releasable to permit joint adjustment of the straightened webs.

14. In a typewriting machine, the combination of a revoluble platen, means for supporting and guiding separate superposed webs to and around the platen, means for holding carbons between said webs, releasable feed rolls to run upon the under side of the platen, means independent of said feed rolls for pressing the superposed webs lightly against the platen at the delivery side thereof, a severing knife to which the inner of said webs may be gaged, and a leading-edge gage for the outer of said webs; said platen shiftable to afford clearance to permit said webs to be straightened sufficiently to admit of the retraction of the carbons therealong.

15. In a typewriting machine, the combination with a revoluble platen, of separate means for guiding separate webs led into the introductory side of the machine, and to assemble them to run around the platen, leading-edge gaging means, means effective to hold one web where gaged, while another web is advanced thereover to be gaged, and a carbon-carrier extending between said webs and retractable to bring the carbon into position for use with a fresh section or page of the web, said platen being shiftable for clearance to permit the webs to be straightened sufficiently for the retraction of the carbon.

16. In a typewriting machine, the combination with a revoluble platen, of separate means for guiding separate webs led into the introductory side of the machine, and to assemble them to run around the platen, leading-edge gaging means, means effective to hold one web where gaged, while another web is advanced thereover to be gaged, and a carbon-carrier extending between said webs and retractable to bring the carbon into position for use with a fresh section or page of the web, said platen being shiftable for clearance to permit the webs to be straightened sufficiently for the retraction of the carbon; said holding means comprising a pressure roll to run lightly upon the webs at the delivery side of the platen, said roll rotatable to permit the advance of the outer web while the pressure of said roll holds the inner web where gaged.

17. In a typewriting machine, the combination with a revoluble platen, of separate means for guiding separate webs led into the introductory side of the machine, and to assemble them to run around the platen, leading-edge gaging means, means effective to hold one web where gaged, while another web is advanced thereover to be gaged, and a carbon-carrier extending between said webs and retractable to bring the carbon into position for use with a fresh section or page

of the web, said platen being shiftable for clearance to permit the webs to be straightened sufficiently for the retraction of the carbon, said gaging means being relatively 5 adjustable.

18. In a typewriting machine, the combination with a revoluble platen, of separate means for guiding separate webs led into the introductory side of the machine, and to assemble them to run around the platen, gaging means for the leading edge of one of said webs, separate gaging means for the leading edge of another of said webs, whereby the webs may be collated upon said 15 platen with the leading edge of one web out of register with the leading edge of another web, means effective to hold one web where gaged while another web is advanced thereover, and a carrier for a carbon extending 20 between said webs, said carrier retractable to bring the carbon into position for use with a fresh section or page of the web, and said platen being shiftable for clearance to permit the webs to be straightened sufficiently 25 for the retraction of the carbon.

19. In a typewriting machine, the combination with a revoluble platen, of separate means for guiding separate webs led into the introductory side of the machine, and to assemble them to run around the platen, gaging means for the leading edge of one of said webs, separate gaging means for the leading edge of another of said webs, whereby the webs may be collated upon 30 said platen with the leading edge of one web out of register with the leading edge of another web, means for holding the under web, comprising a pressure roll to run lightly upon the webs at the delivery side of the 35 platen, said roll rotatable to permit advance of the outer web while said roll by its pressure holds the inner web where gaged, and a carrier for a carbon extending between said webs, said carrier retractable to bring 40 the carbon into position for use with a fresh section or page of the web, and said platen being shiftable for clearance to permit the webs to be straightened sufficiently 45 for the retraction of the carbon.

50 20. In a typewriting machine, the combination with a revoluble platen, of separate means for guiding separate webs led into the introductory side of the machine, and to assemble them to run around the platen, gaging means for the leading edge of one of said webs, separate gaging means for the leading edge of another of said webs, whereby the webs may be collated upon said platen with the leading edge of one web out of register 55 with the leading edge of another web, means effective to hold one web where gaged while another web is advanced thereover, and a carrier for a carbon extending between said webs, said carrier retractable to bring the 60 carbon into position for use with a fresh section or page of the web, and said platen being shiftable for clearance to permit the webs to be straightened sufficiently 65 for the retraction of the carbon.

tion or page of the web, and said platen being shiftable for clearance to permit the webs to be straightened sufficiently for the retraction of the carbon, the gage for the inner web being in the form of a knife edge, 70 and the gage for the outer web being adjustable relatively to said knife edge.

21. In a typewriting machine, the combination with a revoluble platen, of separate means for guiding separate webs led into the introductory side of the machine, and to assemble them to run around the platen, gaging means for the leading edge of one of said webs, separate gaging means for the leading edge of another of said webs, whereby the webs may be collated upon said platen with the leading edge of one web out of register with the leading edge of another web, means effective to hold one web where gaged while another web is advanced thereover, and a carrier for a carbon extending between said webs, said carrier retractable to bring the carbon into position for use with a fresh section or page of the web, and said platen being shiftable for clearance to permit the webs to be straightened sufficiently 85 for the retraction of the carbon, said gaging means being relatively adjustable.

22. In a typewriting machine, the combination with a revoluble platen, of means 95 at the introductory side of the machine to receive superposed webs and guide them to and around the platen, means for retracting a carbon lying between the webs, means at the delivery side of the platen for severing 100 the webs transversely, and means at the delivery side of the machine effective to retain the inner web while the outer web is advanced thereover, and to hold the outer web where adjusted; said platen shiftable for 105 clearance to permit the sheets to be straightened sufficiently to allow the retraction of the carbon.

23. In a typewriting machine, the combination with a revoluble platen, of means 110 at the introductory side of the machine to receive superposed webs and guide them to and around the platen, means for retracting a carbon lying between the webs, means at the delivery side of the platen for severing 115 the webs transversely, and means at the delivery side of the machine effective to retain the inner web while the outer web is advanced thereover, and to hold the outer web where adjusted; said platen shiftable for 120 clearance to permit the sheets to be straightened sufficiently to allow the retraction of the carbon, and said holding means releasable to permit the carbon to be drawn back 125 between the webs.

24. In a typewriting machine, the combination with a revoluble platen and means to conduct superposed webs to and around the platen, of an adjustable leading-edge gage for one of said webs, and a second in- 130

dependently-adjustable leading-edge gage for another of said webs.

25. In a typewriting machine, the combination with a revoluble platen and means to conduct superposed webs to and around the platen, of an adjustable leading-edge gage for one of said webs, a second independently-adjustable leading-edge gage for another of said webs, and means between 10 said gages and the printing line for severing the webs transversely.

26. In a typewriting machine, the combination with a revoluble platen and means to conduct superposed webs to and around the platen, of a table at the delivery side of the platen, a gage thereon for one of said webs, a table overlying said table, and a gage upon said overlying table for another of said webs:

20 27. In a typewriting machine, the combination with a revoluble platen and means to conduct superposed webs to and around the platen, of a table at the delivery side of the platen, a gage thereon for one of said webs, a table overlying said table, a gage upon said overlying table for another of said webs, means for severing the webs transversely, and a third gage for coöperating with said severing means to determine the 30 length of the outer web.

28. In a typewriting machine, the combination with a revoluble platen and means to conduct superposed webs to and around the platen, of a table at the delivery side of the platen, a gage thereon for one of said webs, a table overlying said table, a gage upon said overlying table for another of said webs, means for severing the webs transversely, a third gage for coöperating with 40 said severing means to determine the length of the outer web, and an additional table being provided on which to adjust the leading portion of the outer web to said third gage.

45 29. In a typewriting machine, the combination with a revoluble platen and means to conduct superposed webs to and around the platen, of an adjustable leading-edge gage for one of said webs, and a second independently-adjustable leading-edge gage for another of said webs, said second gage having a range of adjustment to exceed the 50 length of the page to be torn off from the web.

55 30. The combination with a revoluble platen, of a table at the delivery side thereof, a leading-edge gage upon said table, a second table overlying said table and gage, and a second gage upon said second table.

60 31. The combination with a revoluble platen, of a table at the delivery side thereof, a leading-edge gage upon said table, a second table overlying said table and gage, a second gage upon said second table, a third

table above said second gage, and a third 65 gage upon said third table.

32. The combination with a revoluble platen, of a table at the delivery side thereof, a leading-edge gage upon said table, a second table overlying said table and gage, 70 a second gage upon said second table, and means upon the first table for supporting a feed roll to run upon the webs at the delivery side of the platen, for holding the under web where gaged, while permitting 75 the outer web to be advanced thereover.

33. In a typewriting machine, the combination with a revoluble platen and means to receive superposed webs and guide them to 80 and around the platen, of a table at the delivery side of the platen, and a clip upon said table for holding one web while another web is adjusted thereover.

34. In a typewriting machine, the combination with a revoluble platen and means 85 to receive and conduct to and around the platen superposed webs, of a table at the delivery side of the platen, and a series of clips, one in advance of another, for use alternately to retain such web or webs as 90 have been adjusted while another web is adjusted thereover.

35. In a typewriting machine, the combination with a revoluble platen and means to receive and conduct to and around the 95 platen superposed webs, of a table at the delivery side of the platen, a series of clips, one in advance of another, for use alternately to retain such web or webs as have 100 been adjusted while another web is adjusted thereover, and a gage upon said table to which the leading edges of the webs may be adjusted.

36. In a typewriting machine, the combination with a revoluble platen and means to receive and conduct to and around the platen superposed webs, of a table at the delivery side of the platen, a series of clips, one in 110 advance of another, for use alternately to retain such web or webs as have been adjusted while another web is adjusted thereover, a gage upon said table to which the leading edges of the webs may be adjusted, and a second table overlying the first and also having a gage for the leading edges 115 of several webs which may be retained by said clips.

37. In a typewriting machine, the combination with a revoluble platen and means to receive webs and guide them to and 120 around the platen, of means for retracting a carbon inserted between the webs, a table at the delivery side of the platen, a leading-edge gage upon said table, and a clip upon said table for holding one web while another web is adjusted thereover to said gage.

38. In a typewriting machine, the combination with a revoluble platen, of a table at

- the delivery side of the platen, and a series of clips, one in advance of another, for use alternately to retain such work as has been adjusted while another work is adjusted 5 thereover.
39. In a typewriting machine, the combination with a revoluble platen, of a table at the delivery side of the platen, a series of clips, one in advance of another, for use alternately to retain such work as has been adjusted while another work is adjusted thereover, and a gage upon said table to which the leading edges of the work may be adjusted.
40. In a typewriting machine, the combination with a revoluble platen, of a table at the delivery side of the platen, a series of clips, one in advance of another, for use alternately to retain such work as has been adjusted while another work is adjusted thereover, a gage upon said table to which the leading edges of the work may be adjusted, and a second table overlying the first and also having a gage for the leading edges 25 of certain work which may be retained by said clips.
41. In a typewriting machine, the combination with a revoluble platen and means for leading a web to and around the same, of a spool-holder for a separate web to overlie said web around the platen, means for guiding the separate web into the typewriting machine, said guiding means including a part so placed that a loop of web may form between the spool and the typewriting machine, and means to be driven by the first web for rotating said spool to pay off the web therefrom.
42. In a typewriting machine, the combination with a revoluble platen and means for leading a web to and around the same, of a spool-holder for a separate web to overlie said web around the platen, means for guiding the separate web into the typewriting machine, said guiding means including a part so placed that a loop of web may form between the spool and the typewriting machine, and means to be driven by the first web for rotating said spool to pay off the web therefrom, said rotating means including a pair of pressure rolls between which said first web passes, and also including a connection from one of the rolls of said pair to said spool.
43. In a typewriting machine, the combination with a revoluble platen and means for leading a web to and around the same, of a spool-holder for a separate web to overlie said web around the platen, means for guiding the separate web into the typewriting machine, said guiding means including a part so placed that a loop of web may form between the spool and the typewriting machine, means to be driven by the first web for rotating said spool to pay off the web therefrom, said rotating means including a pair of pressure rolls between which said first web passes, and also including a connection from one of the rolls of said pair to said spool.
44. In a typewriting machine, the combination with a rotary platen, means for leading a web to and around the same, and means for driving the platen and web, of a spool-holder for a separate web to overlie the first web around the platen, means to guide the separate web so that a loop of web may form between the spool and the typewriting machine, a pair of pressure rolls between which the first web feeds, a carriage device for said platen, said pressure rolls and said guiding means, a stationary shaft to which one of said pressure rolls is splined, a stationary spool-holder for the coil or spool of web, a roll to run upon the coil or spool of web, and a driving connection from said shaft to the last-mentioned roll.
45. In a typewriting machine, the combination with a rotatable platen, of means for supporting and guiding a plurality of plies of continuous web to and around the platen, means for supporting and guiding a separate sheet, means for carrying carbon sheets interleaved between the plies of said web and said sheet, means for swinging said platen so that said carbon sheets may be retracted, a gage for said continuous web, and a gage for said separate sheet, whereby said sheet may be placed in collation with said web.
46. In a typewriting machine, the combination with a rotatable platen and a carriage mechanism, of a carbon-carrier mounted on said carriage mechanism for retracting the carbons, means over which a continuous web is guided from the carbon-carrier to and under the platen, and a table upon said carriage mechanism beneath said carbon-carrier for supporting and guiding a separate sheet to and under the platen, said platen being swingable to permit the web and sheet to be straightened sufficiently to permit the retraction of the carbons therealong and to permit the advancement of the separate sheet to and under the platen.
47. In a typewriting machine, the combination with a rotatable platen, of means to conduct superposed webs and a separate sheet to and around the platen, a table at the delivery side of the platen, a gage thereon for said webs, a table overlying said table, a gage upon said overlying table for said sheet, and means having a fixed relation to the writing line for severing said webs transversely, said first gage being adjustable.

relatively to said severing means, and said second gage being adjustable relatively to the writing line, whereby said sheet may be placed in collation with said webs.

48. In a typewriting machine, the combination with a rotatable platen, of means to conduct superposed webs to and around the platen, means for severing said webs transversely, said means having a fixed relation to the writing line, a gage for said webs

adjustable relatively to the severing means, means to conduct a separate sheet to and around the platen, and a gage for said sheet adjustable to place said sheet in collation with the webs.

BURNHAM C. STICKNEY.
